(57) CLAIM

The ornamental design for a video monitor, as shown and described.

DESCRIPTION

FIG. 1 is a perspective view of a monitor showing my new design;

FIG. 2 is a front elevational view thereof;

FIG. 3 is a rear elevational view thereof;

FIG. 4 is a left-side elevational view thereof;

FIG. 5 is a top plan view thereof;

FIG. 6 is a bottom view thereof;

FIG. 7 is a left-side elevational view showing the display member of the present design in a backwardly tilted position; and,

FIG. 8 is a top plan view showing the display members of the present design rotating left and right sides.
